[57] CLAIM

The ornamental design for a wall outlet box for a central vacuum cleaning system, as shown and described.

DESCRIPTION

FIG. 1 is a perspective view of a wall outlet box for a central vacuum cleaning system, showing my new design;

FIG. 2 is a right end elevational view thereof, the left end view being a mirror image;

FIG. 3 is a front elevational view thereof.

FIG. 4 is a top plan view thereof; and

FIG. 5 is a bottom plan view thereof.

The wall shown in broken lines in FIGS. 2, 4, and 5 is for illustrative purposes only and forms no part of the claimed design.

FIG. 1

FIG. 2

FIG. 3

FIG. 4

FIG. 5
